SPARK PLUG

Clinton Falor, Akron, Ohio

Application June 15, 1934, Serial No. 730,812

1 Claim. (Cl. 123—169)

This invention relates to new and useful improvements in spark plugs for internal combustion engines.

The primary object of my invention is to provide a spark plug that permits the elimination of the ordinary ground point and at the same time will give more spark with less resistance and produce quicker starting action in a motor.

In one form of my invention, I provide the shell or sleeve which surrounds the porcelain electrode with a metal plug or ring which may be used as an insert in the base of the latter or suitably secured to the lower end of the base.

In another form of my invention, the plug or ring is provided with a plurality of spark points.

In still another form of my invention, the spark point which takes the place of the ordinary ground point is adjustable and in a still further form where a spark plug of the solid type is used, 20 an opening is bored in the lower end of the metal base around the spark point of the porcelain shell.

With the foregoing and other objects in view that will appear as the nature of my invention 25 is better understood, the same consists in the novel features of construction, combination and arrangement of parts illustrated in the accompanying drawings and more particularly pointed out in the appended claim.

30 In the accompanying drawings, which are for illustrative purposes only and are therefore not drawn to scale:

Figure 1 is a side elevation, partly in section, of a spark plug provided with a metal plug or ring used as an insert.

Figure 2 is an end view.

Figure 3 is a sectional view of the lower end of a spark plug, showing another form of plug or ring.

40 Figure 4 is a side elevation, partly in section, of a spark plug of the solid type, showing how the lower end of the base is formed with an opening to receive the spark point of the porcelain shell.

45 Figure 5 is a sectional view of the lower end of the spark plug, showing how a copper collar may be used to center the lower end of the porcelain electrode.

50 Figure 6 is a longitudinal sectional view, showing another form of opening in the lower end of the shell or sleeve which surrounds the porcelain electrode.

55 Figure 7 is a plan view of another form of insert.

Figure 8 is a vertical transverse section, taken on line 8—8 of Figure 7.

Figure 9 is a plan view of still another form of device, which may be welded or otherwise attached to the base of the metal shell or sleeve 5 of the spark plug.

Figure 10 is a vertical transverse section, taken on line 10—10 of Figure 9.

Figure 11 is a plan view of a metal plug or ring with a plurality of spark points used as an 10 insert in the base of the shell.

Figure 12 is a vertical transverse section, taken on line 12—12 of Figure 11.

Figure 13 is a view similar to Figure 12, showing how the metal plug or ring illustrated in 15 Figure 11, may be secured by pins to the lower end of the base of the shell.

Figure 14 is a plan view of a still further form of the device, which may be welded or otherwise secured to the base of the spark plug shell. 20

Figure 15 is a vertical transverse section, taken on line 15—15 of Figure 14.

Figure 16 is a plan view of another form of plug or ring, which is used as an insert in the lower end of the shell base. 25

Figure 17 is a vertical transverse section, taken on line 17—17 of Figure 16.

Figure 18 is a plan view of a plug or ring with an adjustable spark point and Figure 19 is a transverse section, taken on line 19—19 of Fig- 30 ure 18.

Referring to the drawings for a more particular description of my invention and in which drawings like parts are designated by like reference characters throughout the several views, the 35 numeral 1 designates the porcelain electrode, 2 the exteriorly threaded shell or sleeve surrounding the lower end of the electrode and 3 the spark point or pin carried by the lower end of the latter.

In the form of my invention illustrated in Figures 1 and 2 of the drawings, a metal plug or ring 4 is fitted in the lower end of the shell 2 of the spark plug and is formed in its top wall 5 with a central opening 6 to receive the spark pin 3. The lower end of the spark pin 3 preferably extends somewhat below the larger central opening 7 formed by the body of the plug or ring and the bottom edge of said body may be formed with a flange 8, which fits against the lower edge of the shell 2. 45

In the modified form of my invention illustrated in Figure 3 of the drawings, the metal plug 4 is formed with a central upwardly tapering bore or 50 55

opening 9, which extends the full depth of the plug.

Figure 4 of the drawings illustrates a spark plug of the solid type formed with a central opening 10 in the bottom wall 11 of the base 12 of the shell to receive the spark pin 3 of the porcelain electrode.

In Figure 5 of the drawings, the bottom wall 11' of the base 12' of the shell, is provided with a central opening 10' to receive the spark pin 3 and a copper collar 13 is mounted in the hollow base and fits around the lower end of the porcelain electrode 1. The aforesaid collar serves to keep carbon from accumulating on the lower end of the electrode and also helps to center the electrode.

In the form of my invention illustrated in Figure 6 of the drawings, the solid base of the spark plug shell is formed with a central downwardly tapering opening 15, which receives the upper end of the spark pin 3, and a circular recess 16 below and contiguous to the opening 15, which surrounds the lower end of the spark pin.

Figures 7 and 8 show a metal insert comprising a central circular hub 17 adapted to receive the spark pin 3. The hub 17 is formed with three corresponding radial arms 18, whose outer ends fit in corresponding recesses 19 in the lower edge of the shell 2.

The device shown in Figures 9 and 10 of the drawings, comprises a central collar 20 and two oppositely disposed transverse arms 21, whose outer ends 22 are welded or otherwise secured to the lower end of the shell.

In the form of my invention illustrated in Figures 11 and 12 of the drawings, the device is in the form of a cylindrical plug or ring 23, which fits in the lower end of the shell 2 and is formed at its inner edge with four inwardly extending radial tongues 24, which surround the spark pin 3 and act as spark points.

Figure 13 shows how a cylindrical plug or ring 23' having radial tongues 24' and of the general form illustrated in Figures 11 and 12, may be secured to the lower end of the shell by pins 22'.

In Figures 14 and 15 of the drawings, the device comprises a central hub or collar 25, which surrounds the spark pin 3 and is provided with the outwardly extending radial arms 26, whose outer ends 27 are welded or otherwise secured to the lower end of the shell.

In the form of my invention illustrated in Figures 16 and 17 of the drawings, the device comprises an outer cylindrical ring 28, which fits in the lower end of the shell, and a central hub or collar 29 which surrounds the spark pin 3 and is connected to the outer ring by the intermediate radial arms 30.

In the form of my invention illustrated in Figures 18 and 19 of the drawings, the device comprises a cylindrical ring 31, which fits in the lower end of the shell 2 and whose inner edge is formed with a straight wall or portion 32 and a triangular-shaped spark point forming device 33 which is eccentrically pivoted, as at 34, to the bottom wall of the ring 31. It will be noted that the element 33 may be turned on its pivot to cause any one of its spark points 35 to extend across the straight wall or portion 32 of the ring 31, opposite the spark pin 3 and thus regulate the length of the spark gap.

From the foregoing description taken in connection with the drawings, it is thought that the construction, operation and advantages of my invention will be readily understood without requiring a more extended explanation.

Having described my invention, what I claim as new and desire to secure by Letters Patent, is:

In a spark plug of the character specified, a porcelain core provided at its lower end with a spark pin, an exteriorly threaded shell fitting around the lower end of the electrode, a metal ring fitting in the lower end of the shell and formed at its inner edge with a straight wall or portion and a triangular-shaped spark point forming device eccentrically pivoted to the bottom of said ring and adapted to be turned to cause any one of its points to extend over the straight wall or portion of the ring opposite the spark pin, to regulate the size of the spark gap.

CLINTON FALOR.
